UNITED STATES PATENT OFFICE.

JOHN LEWIS MILTON, OF CLEVELAND, OHIO, ASSIGNOR TO MOTOR IGNITION & DEVICES COMPANY, A CORPORATION OF WEST VIRGINIA.

MAGNETO IGNITION SYSTEM FOR INTERNAL-COMBUSTION ENGINES.

1,421,286.

Specification of Letters Patent. Patented June 27, 1922.

Application filed November 12, 1910, Serial No. 591,930. Renewed November 8, 1919. Serial No. 336,735.

To all whom it may concern:

Be it known that I, JOHN L. MILTON, a citizen of the United States, residing at Cleveland, in the State of Ohio, have invented a certain new and Improved Magneto Ignition System for Internal-Combustion Engines, of which the following is a full, clear, concise, and exact description, reference being had to the accompanying drawings, forming a part of this specification.

My invention relates to magneto ignition systems for internal combustion engines and has for its object the provision of a system and circuit arrangement in which the high tension cabling to the spark plugs is obviated thereby eliminating the cause of much of the trouble to which magneto ignition systems are subject, especially when used on automobiles. It is the object of my invention also to provide a simple yet efficient ignition system of comparatively low cost.

In accordance with my invention, I mount in association with each of the spark plugs of a multiple cylinder engine a separate induction coil or transformer. These are composed of a primary coil of coarse wire wound over a secondary coil of fine wire, both coils being impregnated with vulcanized rubber. These coils have no iron core whereby their coefficient of self induction is low. The generator used in conjunction with these individual coils delivers a low tension alternating current preferably of a voltage rather higher than is ordinarily used in the low tension circuit of a high tension magneto ignition system. The alternating current from the generator is normally delivered through the contacts of an interrupter, one wave being delivered through the primary winding of one coil connected with the spark plug of one cylinder and the next wave being delivered through the primary winding of the next coil associated with the spark plug of the next cylinder, and so on. The contacts through which these alternating current waves are delivered are slowly opened by a suitable cam mechanism at the time when the spark is to pass between the contacts of the plug. The opening of the

circuit through the primary winding of the connected transformer coil causes a condenser, which is bridged across the terminals of the generator coil, to be charged. 55 This surge of current having charged the condenser, it immediately tends to discharge itself through any available path. Since the contacts of the interrupter are made to open slowly, at least as compared with the speed 60 of condenser charges and discharges, the arc which will persist between the contacts of the interrupter provides a path sufficient to carry the discharge from the condenser, the condenser discharge being reinforced by the 65 current wave which is still being delivered from the generator winding. The impulse thus delivered upon the break of the circuit at the interrupter contacts passes through the primary winding of the connected coil 70 thereby inducing a high tension impulse in the secondary winding and it is this secondary impulse of high tension which finds its path across the gap between the contacts of the plug to produce the spark necessary 75 for ignition purposes.

Since the coils may be mounted directly upon the spark plugs, and since it is only a low tension current which is delivered from the generator and interrupter and distributor mechanism to the coils, the cabling is very much simplified, it being necessary to run but a single conductor from each spark plug to the distributor mechanism. Furthermore since these conductors carry 85 only low tension currents, their insulation becomes a matter of great simplicity and consequently reduced expense. It is the high tension cabling of the high tension ignition systems now generally used which is responsible for a very large proportion of the derangement and disability of ignition systems and this large cause of trouble is wholly eliminated in the system of my invention. 90

The details of the best means for carrying 95 out my invention so far as I am aware are shown in the accompanying drawings in which—

Figure 1 is a diagrammatic circuit drawing.

Figure 2 is a view largely in cross section 100 and partially in diagrammatic form show-

ing the construction of a generator, interrupter and distributor which are adapted for use in the circuit of Figure 1.

Figure 3 is a cross sectional view of the 5 generator taken on line 3—3 of Figure 2.

Figure 4 is a view of the interrupter taken on line 4—4 of Figure 2.

Figure 5 is a front elevation of one of the transformer coils.

10 Figure 6 is a side elevation of the same.

Figure 7 is a cross-sectional view of such a coil.

Figure 8 is a plan view of one of the connecting clips.

15 Figures 9 and 10 show the means for fastening the connecting clip to the coil proper.

Figure 11 is a view of a piece of the duplex rubber tape used in making the transformer coils.

20 Figure 12 is a cross sectional view of a mold containing the coil to be vulcanized.

Figure 13 is a cross sectional view of the mold and coil taken on line 13—13 of Figure 12.

25 Figure 14 is a plan of the distributor contact plate.

Before attempting to explain the system and its operation as a whole, I shall describe briefly one of the features which contributes 30 largely to the successful operation of the whole, namely the special transformer coil which is directly associated with each of the spark plugs.

Ordinarily transformer or induction coils 35 used in high tension ignition systems are insulated by wax which permeates the interstices between the several turns of the coil. It is necessary that the turns should be perfectly insulated and that the spaces between 40 the conductors be so filled as to exclude moisture. While a wax impregnated coil serves very well under ordinary conditions, it cannot be associated immediately with the spark plug of an internal combustion engine 45 because of the high temperature and generally the severe conditions to be met in such a location. The heat would melt the wax which would run out of the coil and leave the conductors without proper insulation and 50 without proof against moisture.

In accordance with my invention I provide a coil in which the interstices between the several turns are filled with vulcanized rubber which is a better dielectric than wax and 55 which furthermore is not subject to deterioration by the heat in the vicinity of the spark plug.

In making the coil I provide a vulcanized fiber hub 20, as shown in Figure 7. Then 60 with a suitable arbor I hold the spool heads or flanges 21 in engagement with the ends of the hub while I wind successive layers of wire and rubber.

Rubber is laid in the form of a tape cut 65 from a sheet of material comprising a fabric

backing 22 coated with compounded rubber 23 which contains more or less sulphur. This compounded rubber has not sufficient mechanical strength to permit of its being handled in winding, and I therefore lay a 70 very thin layer of Para gum 24 upon the compounded rubber 23. The compounded rubber is very sticky or tacky and the layer of Para rubber therefore adheres firmly to it.

The sheet of duplex rubber thus prepared 75 is cut into strips or tapes a trifle wider than the distance between the spool heads 21, 21 and the layer of duplex rubber is wound about the hub 20, the fabric 22 being removed from the rubber in this process. The compounded rubber is made to face the center 80 of the coil with the Para rubber outside.

When this layer of rubber has thus been laid, a layer of fine secondary wire is wound over the rubber, the tension being adjusted 85 so that the wire will press down into the rubber. The inner end of the secondary wire is attached to a U-shaped connector 25 which is fitted into the hub before the winding is commenced.

When the first layer of wire has been wound a circlet of the duplex rubber is laid over the wire, whereupon a second layer of wire is wound. In this manner the successive 95 layers of fine wire forming the secondary winding are laid up. When a layer of wire is laid, it presses the rubber between it and the next lower layer not only into the grooves between the conductors which is being laid, but also into the grooves between the conductors of the layer which has been laid. The rubber is thus forced to occupy in large measure the interstices between all of the conductors of the secondary winding.

Since the copper of the conducting wire is 100 subject to attack by the sulphur contained in the compounded rubber when the wound coil is vulcanized, I have found it desirable to tin the copper wire very carefully. The tinned wire is, to a large extent, proof against 105 the attack of the sulphur. I have found, furthermore, that silk covering of the fine secondary wire will not withstand the high temperature necessary to vulcanize the coil. I therefore employ a tinned wire covered 110 with a single layer of cotton. The cotton seems to withstand the process of vulcanization very much better than will the silk which one would ordinarily employ for the secondary winding of a coil used for high 115 tension ignition purposes.

When the several layers of the secondary winding have been laid, I wind two or three layers of the duplex rubber on top of the outside layer and then proceed to wind the 120 coarser layer of primary wire indicated at 26 and distinguished by its size from the finer wire constituting the secondary turns 27. I have found that one layer of primary wire suffices in these coils and either end of 125

the single primary layer is therefore connected with one of the terminal clips 28 or 29, each clip being provided with an eyelet 30 into which one end of the primary winding 5 may be inserted and soldered. The small holes 31 punched in the base of the clip permit the rubber, due to its expansion when vulcanized, to press into these holes to form studs which aid in holding the clip in place. 10 The clip also is bound down by the linen thread 32 which passes about the coil. Over the base of the clip and this linen thread I wind one or more layers of the duplex rubber tape, when the coil is ready to receive the 15 rubber heads 33 and 34, these taking the place of the tinned metal spool heads 21, 21. The heads when applied to the coil are of unvulcanized rubber which sticks quite firmly to the concentric layers of rubber which intervene between the layers of wire. It will 20 be remembered that the tape forming these intervening layers was cut a little wider than the space between the spool heads thus insuring a sufficiency of rubber at the exposed 25 end of each layer. The coil thus formed of wire and uncured rubber, with the connecting clips in place is clamped within the vulcanizing mold shown in Figures 12 and 13. The two halves 35 and 36 of the mold 30 are clamped together by the screws 37, whereupon the plunger 38 is brought to bear smartly upon the coil by means of the pressure screws 39, 39. The capillary vents 40, 40 permit the expulsion of air from the 35 mold.

The mold containing the coil is now heated to a temperature of about 340°, this temperature being maintained for a period of about six hours, when the coil will have been vulcanized. This process of vulcanization completely cements or joins the rubber heads to the layers of rubber which intervene between the layers of wire. Furthermore the process of vulcanization tends to expand the rubber 45 to some extent with the result that wires forming the several turns of the coil become wholly embedded in a practically homogeneous mass of rubber in which there are no air bubbles or pockets. The coil has, therefore, a very high degree of insulation. The vulcanized rubber forms an excellent dielectric and since it may be laid in very thin layers, the resulting coil has an extremely 50 high efficiency in the necessary transformation of current.

As previously explained the two ends of the primary winding are connected respectively to the clips 28 and 29 and the outer terminal of the secondary winding is connected also to one of these clips, as for example, 29. When the vulcanized coil is removed from its vulcanizing mold, a machine screw 41 is inserted through the hole in the center of the hub where it is held in place by 55 a nut 42. Under the head of the screw is

clamped the L-shaped connector clip 43. The connection between the inner end of the secondary winding and this clip 43 is completed by the U-shaped connector 25, it being ordinarily unnecessary to solder the connector to the screw 41 on account of the high tension of the current which is carried from one part to the other.

In Figures 2, 3 and 4 I have illustrated the generator and interrupter and distributor mechanism. A pair of U-shaped permanent magnets 50, 50 embrace the pole pieces 51, 51, the pole pieces being attached to the magnets by the screws shown in dotted lines at 52, 52. The pole pieces in turn are attached 75 by means of the screws 53, 53 to the rocker yoke 54, this yoke having a cylindrical lug or bushing 55 which is journaled in the engine frame indicated at 56. The timing lever mechanism is attached to the arm 57 80 of the yoke whereby the field magnet may be turned forward or back to advance or retard the time of the spark production.

The iron armature 58 is mounted upon the flange 59 of the driving spindle 60, the latter 90 being mounted in ball bearings 61 and 62 carried inside the boss 55. Upon the armature is wound the generating coil 63, the inner terminal being led out through the hard rubber bushed opening 64.

Upon the farther end of the armature is mounted the interrupter supporting disc 65. This disc is provided at the center with a standard 66 upon which is mounted with suitable insulating bushings the distributor 95 brush 67. The inner terminal of the armature winding is connected with this distributor brush by the wire 68. The other terminal of the armature winding is connected by means of the conductor 69 with the adjustable contact point 70. Upon the supporting disk 65 is pivotally mounted also at 71 the interrupter blade 72. At one end the interrupter blade is adapted normally to make connection with the contact 70. At 100 the other end the interrupter blade is provided with a fiber stud 73. It will be apparent that the rotation of the interrupter supporting disc and the interrupter mechanism corresponds with that of the armature. The cylindrical brass shell 74 which is mounted upon the rim turned in the pole pieces 51 is provided with cam surfaces 75 and 76 whereby the rotation of the interrupter disc as indicated by the arrow 77, 110 brings the stud 73 into engagement with the cam surfaces to trip the interrupter blade 72, thus causing the electrical connection with the contact 70 to be interrupted.

Within the space enclosed by the interrupter supporting disk 65 is mounted a condenser 78, this being electrically connected across the terminals of the armature winding as diagrammatically shown.

The distributor brush 67 engages one after 120

- another the distributor contacts 79 and 80. A grounding contact 81 makes continuous connection with the center of the distributor brush 67.
- 5 The operation of the generator mechanism may readily be explained in connection with the operation of the system as a whole and for that purpose reference may be had to Figure 1 of the drawings, where 10 the reference letters corresponding with those shown in the other figures are applied so far as possible. It will be noted that Figure 1 shows the spark plugs 82, 83, 84 and 85 of a four-cylinder engine and corresponding with this a distributor brush 67 which is adapted to make connection successively with the four distributor contacts, each of which leads to one terminal of the primary winding of a transformer coil. The arrangement shown in this Figure 1 is different in 15 this respect from that shown in Figures 2, 3 and 4 where provision is made for but two spark plugs as in a two-cylinder engine. Where a four-cylinder engine is involved, the distributor brush 67 must be geared to the armature of the generator in a two to one ratio so that the armature may make two complete revolutions during a single revolution of the distributor blade. In the construction shown in Figures 2, 3 and 4 it 20 is proper that the distributor blade should make but a single revolution for each revolution of the armature. In Figure 1, therefore, I have designated two diametrically opposite distributor contacts with the reference letters 79 and 80, the other two being designated respectively 79' and 80'.
- The circuit connections will for the most part be apparent from the description already given with respect to Figure 2. It 25 may be pointed out, however, that the interrupter blade 72 is mounted without insulation directly upon the metal parts of the generator. The generator is in turn bolted to the engine frame and the spark plugs are screwed into the metal cylinders of the engine. One contact of each of the spark plugs is grounded therefore as indicated at 30 86 and the interrupter blade is grounded at 87. The grounding contact 81 is connected through a manually operable switch 88 with ground indicated at 89. It will be seen that the connector clips 43 of the transformer coils are connected with the 35 insulated and ungrounded contacts 90 of the spark plugs. The clips 29 which serve as terminals both for the primary and secondary windings of their respective coils being connected by the connectors 91, 91 with the grounded portions of the spark 40 plugs.
- The operation may now be explained. The interrupter contacts are normally closed wherefore the current wave generated upon 45 the rotation of the armature may be traced in Figure 1 from the armature lead 68 to the rotating distributor brush 67, thence through the distributor contact 80 to the primary terminal clip 28 of the transformer coil connected with the spark plug 84, thence 50 through the primary winding of that coil to the terminal 29, thence through the associated connector 91 to ground at 86, thence through ground to the interrupter blade 72 to the closed contact 70 and thence by way 55 of the wire 69 to the other terminal of the armature winding. The cam mechanism which is but diagrammatically shown in Figure 1, is timed to open the interrupter contacts slowly when the spark is to be produced in the engine cylinder. When the interrupter contacts open the path through which current has been flowing through the primary winding of the transformer coil, there is a sudden rush or surge of current 60 into the condenser 78. This flow of current into the condenser takes place simultaneously with a sharp reduction in the amount of current flowing through the primary winding of the transformer coil. This means that 65 the magnetism threading the secondary winding of the coil will be reduced. Almost instantaneously after the surge of current into the condenser there is a recoil or rebound of current which, reinforced by the 70 continuing electromotive force of the generator winding, causes a current to jump the gap between the contacts of the interrupter and to flow through the primary winding of the transformer coil. A small arc will be 75 produced when the interrupter contacts are opened and if they be opened comparatively slowly, the arc will persist long enough to be available to convey the surge or recoil of current delivered by the condenser as just 80 explained. This sharp surge of current which passes through the primary winding of the transformer coil in preference to the coil of the generator causes a rapid increase 85 in the number of lines of force threading the 86 secondary winding of the coil with the result that a high tension current is generated in the secondary winding of the coil and this secondary current finds its path from the clip 29 through the connector 91 to the 90 grounded contact of the plug. The current easily jumps the gap to the insulated contact 90 of the plug and flows through the connector clip 43 to the inner terminal of the secondary winding. I prefer to make the 95 coils without iron cores in order that the reactance to the flow of the condenser discharge may be a minimum. Since the inductive opposition of the generator winding is much greater than that of the primary winding of 100 the transformer coil and since also the continuing electromotive force of the generator opposes the condenser discharge, the impulse of current will flow almost wholly through 105 the primary of the transformer coil.

The gearing 99 by means of which the generator is connected to be driven by the engine is so arranged that an alternating current wave will be generated to fire the 5 several cylinders of the engine in succession. The distributor mechanism connects the coils of the several spark plugs successively in circuit and the current wave is generated during the connection of each such coil.

10 When it is desired to stop the engine, the ignition currents are diverted by closing the manual switch 88. It will be apparent that this switch when closed provides a short circuit to ground over which the current 15 pulses will flow in preference to the primary windings of the coils which are of relatively high resistance.

Having described my invention, I claim as new and desire to secure by Letters 20 Patent:

1. An ignition system for internal combustion engines comprising an alternating current generator, a condenser permanently bridged across the terminals of said generator, 25 a transformer coil comprising a primary winding, a secondary winding in inductive relation to said primary winding; a jump spark circuit including said secondary winding, electrical connections between the terminals of the primary winding of the transformer coil and the terminals of the generator, normally-closed contacts in series with the primary winding, and engine-driven devices for opening said contacts when a spark 30 is to be created within the engine cylinder with which the jump spark circuit is associated.

2. An ignition system for internal combustion engines comprising a magneto generator, a condenser permanently bridged across the generator terminals, a transformer coil comprising a primary winding, a secondary winding in inductive relation to said primary winding, a jump spark circuit 40 including said secondary winding, electrical connections between the terminals of the primary winding and the terminals of the generator, normally-closed contacts in series with the primary winding of the transformer coil, and engine-driven devices for opening said contacts slowly as compared with the speed of the condenser charges and discharges.

3. An ignition system for internal combustion engines comprising an alternating current generator, a condenser permanently bridged across the generator terminals, a plurality of transformer coils each comprising a primary winding normally connected 55 with one terminal of the generator, an engine-driven distributor arranged to connect the other terminals of the primary windings one after another with the second terminal of the generator, a pair of normally-closed 60 interrupter contacts in series with the

primary winding of the transformer coils, engine-driven means for opening said contacts when a spark is to be created in an engine cylinder, a secondary winding in inductive relation to each of said primary 70 windings, and a jump spark circuit including each of said secondary windings.

4. An ignition system for internal combustion engines comprising a magneto generator, a condenser permanently bridged 75 across the generator terminals, a transformer coil comprising a primary winding, a secondary winding in inductive relation to the primary winding, a jump spark circuit including said secondary winding, means for 80 electrically connecting the terminals of the primary winding with the terminals of the generator, normally-closed contacts in series with the primary winding, and engine-driven means for opening said contacts when 85 a spark is to be created in the jump spark circuit.

5. An ignition system for internal combustion engines comprising an alternating current generator, a condenser permanently 90 bridged across the generator terminals, a plurality of transformer coils, each comprising a primary winding, a secondary winding in inductive relation to each of said primary windings, a jump spark circuit including 95 each of said secondary windings, means for electrically connecting a first terminal of each of the primary windings with a generator terminal, a distributor arranged to connect the other generator terminal with 100 a second terminal of each of the primary windings one after another, normally-closed contacts in series with the primary windings, and engine-driven means arranged when a spark is to be created in one of the 105 jump spark circuits to open said contacts slowly as compared with the speed of the condenser charges and discharges.

6. An ignition system for internal combustion engines comprising a magneto generator, a condenser permanently bridged across the generator terminals, a transformer coil comprising a primary winding, a secondary winding in inductive relation to said primary winding, a jump spark circuit 110 including said secondary winding, electrical connections between the terminals of the primary winding and the terminals of the generator, and contact mechanism in series with the primary winding arranged to 115 close the primary circuit when no spark is required and to open said circuit when a spark is required to permit charging of the condenser and then discharge thereof across the air gap of the contacts, substantially as 120 described.

7. In a structure of the class described the combination with an air core transformer of a magneto connected in series with the primary circuit of said transformer, a con- 125 130

denser shunted across said magneto, and means for slowly opening said primary circuit and for closing it.

8. In a structure of the class described the combination with a source of current of a transformer having less inductance than said source of current and having its primary circuit connected in series with said source of current, a condenser shunted across

said source of current, and means for slowly 10 opening said primary circuit and for closing it.

In witness whereof, I hereunto subscribe my name this 22 day of August, A. D. 1910.

JOHN LEWIS MILTON.
